EASEL BACK

Robert L. Wright, Salem, Ohio

Application December 20, 1934, Serial No. 758,447

4 Claims. (Cl. 40—146)

The invention relates to easel backs for display cards, pictures and the like and more particularly to a simple and inexpensive device of this character.

5 Display cards and the like are ordinarily provided with an easel back die stamped from cardboard or the like and permanently attached to the back of the card so that the same may be held in an upright position upon a show case, 10 counter or other surface. The cost of producing such easel backs is considerable, both for the material and labor required. There is also a considerable waste of material as part of the cardboard forming the easel back is cut away 15 by the dies in order to produce the desired shape when the easel back is bent or folded into operative position.

As these easel backs are permanently attached to the back of the display card by mucilage or 20 the like, the cost of the same to large advertisers, who are periodically changing their display cards, is exceedingly high as each new display card is provided with an easel back permanently attached thereto.

25 The object of the present improvement is to provide a simple and inexpensive easel back which may be manufactured with a minimum cost of labor and material and which is detachably secured to the back of the display card or the like so that it may be easily and readily detached therefrom and attached to a new display card, thus saving the expense of providing a new easel back for each new display card.

Another object is to provide an easel back 35 including a piece of cardboard, paper or the like having one or more grooves formed therein, a bent wire brace being detachably received therein, and arranged to be folded against the back of the display card for shipping or storage and 40 to be angularly disposed relative to the card for holding the same in upright position.

The above objects, together with others which will be apparent from the following description and drawing, may be attained by constructing 45 the improved easel back in the manner illustrated in the drawing, in which

Figure 1 is a perspective view of a display card provided with the improved easel back;

Fig. 2, a fragmentary rear elevation of a portion 50 of a display card provided with the improved easel back showing the wire brace folded flat against the card for shipping or storage;

Fig. 3, a vertical sectional view through the lower portion of a display card provided with 55 the improved easel back;

Fig. 4, a section on the line 4—4, Fig. 3;

Fig. 5, a similar section of a modified form of the invention; and

Fig. 6, a detached elevation of the bent wire brace.

Similar numerals refer to similar parts throughout the drawing.

A display card or the like, which may be formed of cardboard or similar material, is indicated generally at 10 and may have any desired advertising matter or the like upon its front surface 11.

10 A small piece of cardboard or the like, which may be in the form of corrugated paper, as indicated at 12 in Figs. 1, 2, 3 and 4, is attached 15 to the rear surface of the display card 10 as by mucilage or the like, being preferably centrally located at the lower portion of said display card as best shown in Fig. 1.

The corrugated paper indicated at 12 may be of 20 any usual and well known kind of corrugated paper having one layer 13 uniformly corrugated, producing a plurality of grooves 14 and ribs 15. If desired, instead of using a corrugated paper, a single sheet of cardboard or the like, as indicated 25 at 12a in Fig. 5, and having a vertical longitudinal groove 16 centrally formed therein by pressing, steaming or the like, may be glued or otherwise attached to the rear surface of the display card 10.

It will be seen that when the cards 12 or 12a 30 are glued to the rear surface of the display card, each of the grooves 14 or 16 provides an elongated casing or tubing adapted to receive one end portion of the wire brace, as will be later described.

The wire brace, as shown detached in Fig. 6, is 35 formed of a single piece of wire and may be of hard blued wire, or spring wire if desired. The wire is bent intermediate its end to form a loop or eye 17 and folded back upon itself for a portion of its length as at 18, the folded back portion being 40 then bent outward as at 19, substantially at right angles to the depending straight attaching leg 20 and terminating in a downwardly and outwardly inclined angular supporting leg 21 preferably having 45 a foot 22 formed at its end in the shape of an eye or loop.

The lower end of the straight attaching leg 20 may be pointed as at 23 in order that it may be easily inserted into one of the tubular casings 50 or grooves 14 or 16. For shipping and storage purposes the wire brace may be located flat against the back of the display card 10, as shown in Fig. 2, with the lower portion of the attaching leg 20 inserted into a tubular casing or groove of the 55

cardboard member 12, the right angle portion 19 of the brace resting upon the top edge of the member 12 as shown.

When it is desired to erect the card 10 upon a show case, counter or the like for display purposes, the wire brace is swung into the position best shown in Figs. 1 and 3, in a plane at right angles to the normal plane of the card 10, and is then pressed downward as shown in said figures, the upper portion of the groove or casing being clamped between the folded back portion 18 and the upper portion of the straight leg 20 so as to hold the wire brace rigidly in the proper position to support the display card in upright position with the lower edge of the display card and the foot 22 of the wire brace resting upon the horizontal surface of the show case, counter or the like on which the card is to be displayed.

The wire brace may be formed of round wire or if desired, it may be formed of a wire having at least one face flattened as shown in Fig. 5, the opposed flat faces of the bent back portions assisting in holding the wire brace rigidly clamped upon the tubular casing 16.

Where it is desired to provide an easel back for display cards of large size, two of the bent wire braces may be used for a single card, the straight legs thereof being inserted into corrugations at spaced points in the corrugated paper card 12.

I claim:

1. In combination with a display card and the like, an easel back therefor including a piece of cardboard attached to the back of said display card and having a vertical groove therein forming a tubular casing, and a wire brace including a straight leg adapted to be received in said tubular casing, a folded back portion adapted to tightly engage the outside of said tubular casing, and an

angular supporting leg extending downward at an angle to the straight leg.

2. In combination with a display card and the like, an easel back therefor including a piece of cardboard attached to the back of said display card and having a vertical groove therein forming a tubular casing, and a wire brace including a straight leg adapted to be received in said tubular casing, a folded back portion adapted to tightly engage the outside of said tubular casing, and an angular supporting leg extending downward at an angle to the straight leg, 5 10 15

3. In combination with a display card and the like, an easel back therefor including a piece of cardboard attached to the back of said display card and having a vertical groove therein forming a tubular casing, and a wire brace including a straight leg adapted to be received in said tubular casing, a folded back portion adapted to tightly engage the outside of said tubular casing, a portion extending substantially at a right angle to the folded back portion, and an angular supporting leg extending downward at an angle to the straight leg.

4. In combination with a display card and the like, an easel back therefor including a piece of corrugated paper attached to the back of said display card, and a wire brace including a straight leg adapted to be received in one of the corrugations of said corrugated paper, a folded back portion adapted to tightly engage the outside of said corrugated paper, and an angular supporting leg 35 30 35 extending downward at an angle to the straight leg.

ROBERT L. WRIGHT.
